US00D772209S

(12) **United States Design Patent** (10) **Patent No.:** **US D772,209 S**
(45) **Date of Patent:** **** Nov. 22, 2016**

(54) **CASE FOR ELECTRONIC DEVICE**

(71) Applicants: **Dae-Young Kim**, Seoul (KR); **Young Kwang Hyun**, Seoul (KR)

(72) Inventors: **Dae-Young Kim**, Seoul (KR); **Young Kwang Hyun**, Seoul (KR)

(73) Assignee: **SPIGEN KOREA CO., LTD.**, Geumcheon-Gu, Seoul (KR)

(**) Term: **14 Years**

(21) Appl. No.: **29/494,067**

(22) Filed: **Jun. 17, 2014**

(51) LOC (10) Cl. **14-03**

(52) U.S. Cl.

USPC **D14/250**

(57) **CLAIM**

The ornamental design for a case for electronic device, as shown and described.

DESCRIPTION

FIG. 1 is a front perspective view of a case for electronic device, comprised of inner portion and outer portion, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded front perspective view thereof showing the inner and outer portions of the case for electronic device separated for clarity of disclosure.

The broken lines depict of unclaimed environment and form no part of the claimed design.

1 Claim, 9 Drawing Sheets
